UNITED STATES PATENT OFFICE

ROBERT J. McFALL, OF LYONHURST, VIRGINIA

LEATHER-MEASURING MACHINE

Application filed November 16, 1923, Serial No. 675,218. Renewed June 3, 1929.

This invention relates to machines for measuring flat articles or materials of irregular outline, such as hides, skins, leather, and the like, and particularly to machines of this character of the type wherein a hide or the like, when passed through the machine, is theoretically divided into a plurality of imaginary strips of equal width, the length of the several strips simultaneously measured, and the lengths (and consequently the areas) of all of said strips cumulated to determine the total area of the hide.

The invention has for its object the provision of a novel and simplified, but accurate, machine of this character comprising improved means for feeding the material to be measured through the machine, said feeding means having combined therewith contact mechanism in the form of a series of contact members actuated respectively by the passage of the material, in accordance with the number and length of the several imaginary strips into which the latter is divided, together with simple and effective cumulating mechanism controlled by said contact mechanism, said cumulating mechanism being preferably operated by fluid pressure, whose flow to a suitable meter is controlled by the several contact members respectively.

The foregoing and other objects of the invention, together with means whereby the same may be carried into effect, will best be understood from the following description of one form or embodiment thereof illustrated in the accompanying drawings. It will be understood, however, that the particular construction described and shown has been chosen for illustrative purposes merely, and that the invention, as defined by the claims hereunto appended, may be otherwise practised without departing from the spirit and scope thereof.

In said drawings:

Fig. 1 is a diagrammatic end elevation of the machine, partly in section on the line 1—1, Fig. 2, and with the adjacent end frame member removed.

Fig. 2 is a plan view of one end of the machine, the piping being broken away and the meter omitted.

Fig. 3 is a detail section on the line 3—3, Fig. 2.

The hides or other articles to be measured are fed over a table 10 by means of a bed roll 11 mounted on a shaft 12, journalled in suitable end frame members 13. Said bed roll is suitably driven from any convenient source of power, as by a belt 14 which passes about a pulley 15 on the shaft 12. Cooperating with the bed roll 11 to insure the necessary traction between the latter and the material to be measured, is a series of pressure or traction disks 16 supported by a shaft 17 which extends across the machine above the bed roll substantially parallel to the shaft 12 and is suitably supported at its ends by the end frame members 13. The shaft 17 is of elliptical or otherwise flattened cross section of greater horizontal than vertical diameter. The traction disks 16 are formed with central circular openings 18 of a diameter at least equal to, and preferably slightly greater than, the major diameter of the shaft 17. Between the several traction disks 16, and between the endmost disks of the series and frame members 13 are spacing disks 19 of smaller diameter than said traction disks, said spacing disks having central openings shaped substantially to fit the shaft 17, whereby said spacing disks are held fast on said shaft against rotation. The traction disks 16, however, are loose on the shaft, being free to rotate thereon and being also permitted a slight vertical movement, whereby said disks are severally permitted to rest by gravity upon the material and to follow the profile thereof, while acting to hold the same in close engagement with the bed or feeding roll.

Between the traction disks 16, the bed roll 11 is formed with a series of circumferential grooves 20 in which are positioned contact members 21 whose free forward ends 22 are located substantially in the plane of the axes of the shafts 12 and 17, and are shaped to be engaged and depressed by the material to be measured as the latter passes over said bed roll and through the machine. The contact members 21 comprise levers pivoted at 23 to bracket arms 24 suitably supported, as upon a

valve chest 25 which extends horizontally across the machine, preferably immediately at the rear of the bed roll, said valve chest forming a part of the cumulating mechanism.

5 The rear end of each of the contact members 21 is received between a pair of collars 26 and 27 on a valve stem 28 which extends into the valve chest 25 through an opening 9 in the top wall of the latter. Beyond the valve 10 stems 28, the rear ends of the contact members are connected by springs 30 with the valve chest, said springs tending normally to hold the free forward ends 22 of the contact members projected out of the grooves 20 into 15 positions to be engaged by the leather or other material to be measured, the precise normal position of each contact member being determined by a stop screw 31 carried thereby and engaging the top of the valve chest.

20 The valve chest 25 is divided longitudinally by a vertical partition 32 and is further longitudinally divided at one side of said vertical partition by a horizontal partition 3, thereby forming within said valve chest three longitudinal chambers 4, 5, and 6. The inner ends 25 of the valve stems 28 are angularly offset and extend through slots 7 in the partition 32 at the opposite side of which said stems are connected with sliding valves 8 which are held seated against said partition by springs 2 connected with the valve stems. Each valve 8 cooperates with two ports 40 and 41 alternatively. It will be understood that the contact members 21 may be of any desired or required number, and that the valves 8, pairs of ports 40 and 41, and valve stems 28 are equal respectively in number to the contact members.

25 Suitably geared to the shaft 12 of the bed 40 roll 20, so as to be driven thereby, is a pump 42. Said pump may be of the rotary type, and, as herein shown, the shaft 43 thereof is connected by skew gears 44 with said shaft 12. Said pump is adapted to maintain a 45 circulation of fluid, preferably oil or other liquid, through a closed fluid circuit including a pipe 45 communicating with the intake of the pump and a pipe 46 communicating with the discharge thereof. The pipe 46 50 communicates with the chamber 4 of the valve chest 25. Leading from the chamber 6 of said valve chest is a pipe 47 which leads to a meter 48 of a type suitable for measuring the flow of fluid, said meter constituting the 55 cumulator of the machine. The discharge from the meter 48 is returned to the pump through the pipe 45, which is connected with the chamber 5 of the valve chest 25 by a branch pipe 49 constituting a by-pass about 60 the meter. If desired, the pipes 45 and 47 may be connected by another by-pass pipe 50 provided with a manually adjustable valve 51 by which the flow of fluid through the 65 meter may be controlled in order to calibrate the latter.

When no leather is passing through the machine, the contact members 21 are normally held by the springs 30 in the position shown in Fig. 1, thereby holding all of the valves 8 in the position to open the ports 40 and close the ports 41, so that the flow of fluid from the pump to the meter is impeded or cut off, said fluid being returned to the pump through the by-pass 49. When the end 22 of any contact member 21 is depressed by leather passing over the bed roll, the corresponding valve 8 will be shifted to close its port 40 and open its port 41, thereby dividing the flow of fluid from the pump and diverting a portion thereof through the port 41, chamber 6 and pipe 47 to the meter 48. The portion of the flow so diverted to the meter will depend upon the number of contact members actuated by the leather, consequently upon the width of the latter and the corresponding number of imaginary strips into which it is theoretically divided, while the period during which any portion of such flow is so diverted will depend upon the period of depression of the several contact members, and consequently upon the length of the respective strips, the flow of fluid from the pump being constant and proportional to the speed of travel of the leather, since said pump is geared to the bed roll 11 by which said leather is fed. The total portion of the flow from the pump which passes through the meter is therefore proportional to the area of the hide, so that, by properly calibrating the meter by means of the valve 51, the area of any hide, or the grand total of the areas of all hides passed through the machine, may be directly registered by said meter.

The arrangement of the piping shown in Fig. 1 is merely diagrammatic, it being understood that the precise disposal and arrangement of the pipes may be in accordance with convenience, the desired position of the meter, and the design of any particular machine.

Having thus described my invention, I claim:

1. In a machine for measuring leather and the like, in combination, a bed member, a shaft above said bed member, and a series of independent traction disks directly and loosely mounted on said shaft.

2. In a machine for measuring leather and the like, in combination, a bed member, a shaft above said bed member, and a series of independent traction disks directly and loosely mounted on said shaft and rotatable and vertically movable thereon.

3. In a machine for measuring leather and the like, in combination, a bed member, a shaft above said bed member, said shaft being of greater horizontal than vertical diameter, and a series of traction disks independently mounted on said shaft, said disks having central openings of a diameter at least

- as great as the major diameter of said shaft to receive the latter.
4. In a machine for measuring leather and the like, in combination, a bed member, a shaft above said bed member, a series of independent traction disks directly and loosely mounted on said shaft, and spacing disks on said shaft between said traction disks.
5. In a machine for measuring leather and the like, in combination, a bed member, a shaft above said bed member, said shaft being of greater horizontal than vertical diameter, a series of traction disks independently mounted on said shaft, said disks having central openings of a diameter at least as great as the major diameter of said shaft to receive the latter, and spacing disks on said shaft between said traction disks and having openings shaped to fit said shaft.
6. In a machine for measuring leather and the like, the combination with a feeding member, of a contact member located in said feeding member and actuated by the material fed by said feeding member, cumulating mechanism operated by the passage of an actuating medium therethrough, and means operated by said contact member for controlling the passage of said medium through said cumulating mechanism.
7. In a machine for measuring leather and the like, in combination, a bed roll having circumferential grooves, contact members located in said grooves, normally projecting upwardly therefrom, and depressed by the material during its passage over said bed roll, cumulating mechanism, and devices operated by said contact members respectively for controlling said cumulating mechanism.
8. In a machine for measuring leather and the like, in combination, a bed roll having circumferential grooves, means for rotating said roll to feed the material to be measured through the machine, contact members located in said grooves, normally projecting upwardly therefrom, and depressed by the material during its passage over said bed roll, cumulating mechanism, and devices operated by said contact members respectively for controlling said cumulating mechanism.
9. In a machine for measuring leather and the like, in combination, measuring means, a cumulator, an actuator therefor, and means controlled by said measuring means for transmitting the power from said actuator to said cumulator or for diverting the same back to said actuator.
10. In a machine for measuring leather and the like, the combination with measuring mechanism, of fluid operated cumulating mechanism, and means controlled by said measuring mechanism for controlling the flow of fluid through said cumulating mechanism.
11. In a machine for measuring leather and the like, the combination with measuring
- mechanism, of hydraulic cumulating mechanism, and means controlled by said measuring mechanism for controlling the flow of liquid through said cumulating mechanism.
12. In a machine for measuring leather and the like, in combination, a fluid operated cumulator, and means operated by passage of material to be measured through the machine for controlling the passage of fluid through said cumulator.
13. In a machine for measuring leather and the like, in combination, a fluid operated cumulator, and a series of valves independently operated by passage of material to be measured through the machine for controlling the passage of fluid to said cumulator.
14. In a machine for measuring leather and the like, the combination with a fluid operated cumulator, of a series of contact members independently operated by passage of the material to be measured through the machine, and means operated by said contact members for controlling the passage of fluid to said cumulator.
15. In a machine for measuring leather and the like, the combination with a fluid operated cumulator, of a series of contact members independently operated by passage of the material to be measured through the machine, and a series of valves respectively operated by said contact members for controlling the passage of fluid to said cumulator.
16. In a machine for measuring leather and the like, the combination with a fluid operated cumulator, of means for inducing a flow of fluid through said cumulator at a rate proportional to the rate of passage of the material to be measured through the machine.
17. In a machine for measuring leather and the like, the combination with a fluid operated cumulator, of means for supplying a constant flow of fluid, and means controlled by the passage of the material to be measured through the machine for dividing said flow and diverting a variable portion thereof to said cumulator.
18. In a machine for measuring leather and the like, in combination, means for feeding material to be measured through the machine, means for supplying a flow of fluid at a rate proportional to the rate of movement of said feeding means, a fluid operated cumulator, and means controlled by the passage of said material through the machine for diverting a variable portion of said flow to said cumulator.
19. In a machine for measuring leather and the like, means for supplying a continuous flow of fluid, means controlled by the passage of the material to be measured through the machine for dividing said flow into relatively variable parts and means for measuring one of said parts.
20. In a machine for measuring leather and the like, in combination, a roll for feeding the

material to be measured, a pump operated by said roll, a meter, and means operated by the passage of said material through the machine for directing the fluid from said pump to said meter or returning the same to said pump.

5 21. In a machine for measuring leather or the like, the combination with a constantly operating pump and a meter connected in a closed fluid circuit, of a by-pass about said 10 meter, and means operated by passage of the material to be measured through the machine for controlling said by-pass.

15 22. In a machine for measuring leather or the like, the combination with a constantly operating pump and a meter connected in a closed fluid circuit, of a by-pass about said 20 meter, a series of independent valves for alternatively opening said by-pass or the portion of said circuit leading to said meter, and a series of contact members operated by passage of the material to be measured through the machine for controlling said valves respectively.

25 In testimony whereof I affix my signature.
